INVENTOR.

John C. Schelter
By his Attorney,
Nelson W. Howard

UNITED STATES PATENT OFFICE.

JOHN C. SCHELTER, OF ROCHESTER, NEW YORK, ASSIGNOR TO FITZ-EMPIRE DOUBLE PIVOT LAST COMPANY, OF AUBURN, MAINE, A CORPORATION OF MAINE.

SHOE-LAST.

1,350,340.

Specification of Letters Patent. Patented Aug. 24, 1920.

Application filed October 1, 1918. Serial No. 256,443.

To all whom it may concern:

Be it known that I, JOHN C. SCHELTER, a citizen of the United States, residing at Rochester, in the county of Monroe and 5 State of New York, have invented certain Improvements in Shoe-Lasts, of which the following description, in connection with the accompanying drawings, is a specification, like reference characters on the drawings indicating like parts in the several 10 figures.

This invention relates to the manufacture of boots and shoes and comprises a novel last for use in the manufacture of such 15 articles.

One of the principal objections to shoes of the McKay and turn types is the presence of stitches or other fastenings in the inside of the shoe, where they cause discomfort to the 20 wearer and mar the appearance of the shoe. The use of an inside slip sole has not entirely avoided this objection, and attempts have been made to position the fastenings in a channel formed in the upper face of the 25 insole. Great difficulty in keeping the channel flap in temper has been experienced, however, with consequent failure to close the channel properly and smoothly after the attachment of the sole.

30 It has been proposed broadly to treat a part of the shoe lying next to the last, in particular a channel flap, after the shoe is assembled on the last, to insure that it will be in temper for subsequent operations, and 35 in particular to keep in temper the turned up channel flap of an insole such as above described during the lasting and sole laying operations, so that it will be in proper condition to be laid and cemented smoothly 40 after the sole attaching operation.

A last adapted for the practice of the described process, arranged with a cavity in the bottom to hold means, such as a dampened tempering pad, for treating a part of 45 a shoe (in particular as herein illustrated the channel flap) while the shoe remains on the last, has also been proposed. The present invention provides a last with a cavity having waterproof walls in order to prevent 50 damage to the body of the last by moisture, the cavity being adapted to hold a dampened tempering pad. Preferably, also, the narrow outside rim of the cavity is formed of some tough material, such as fiber, to enable it to withstand repeated tacking. 55

These and other features of the invention will be understood from the following description of the invention in connection with the attached drawings which illustrate the practice of the process and a preferred 60 form of the last embodying the invention and by which the process may be practised.

In the drawings,

Figure 1 shows a perspective of the last. 65

Fig. 2 is a cross section showing the step of lasting the upper.

Fig. 3 is a cross section of the completed shoe, and

Fig. 4 shows the insole.

The main body 10 of the last may be of any desired type, as for example, solid, block, or hinge. The bottom of the last is formed preferably of some waterproof material 12, as fiber, and contains a longitudinal depression 14. In the last shown this depression extends from near the tip to the metal heel plate 16. It is not as wide as the bottom of the last, and leaves a strip 18 in the position of the usual last bottom approximately $\frac{1}{2}$ inch wide around the edge of the tread face. The strip 18 may be made integral with the waterproof last bottom 12, or may be removable, if desired, as indicated in dotted lines in Fig. 2, and will preferably be formed of material adapted to permit tacking. A dampened pad 20, of spongy material, as for example felt, is placed in the depression 14. 70

In accordance with my invention the last 90 is used as follows in the manufacture of McKay shoes:—

An insole 22 is channeled in its upper surface, as at 24. This channel runs preferably on each side of the insole from the heel 95 breast portion to a point near the toe tip. The channel is preferably not run around the toe tip for the reason that such procedure will weaken the insole too much at this point, the insole stock used in shoes of 100 this type being often very inferior; and for the further reason that a channel flap at the extreme tip would interfere with the last pulling.

The insole is applied to the last with the 105 channel flaps turned back into the depression 14 where the dampened pad 20 keeps them in proper temper (see Fig. 2). At the same time, the waterproof bottom prevents 110 injury to the wooden body of the last from

the continuous presence of the damped pad 20. The upper 26 is then lasted and is preferably cemented to the insole 22, a few lasting tacks 28 being driven to hold it 5 until the cement has set, and removed before the last pulling. The fiber rim 18 has been found to permit repeated tacking much more advantageously than wood would do. Such treatment of a wooden rim of such small 10 width would soon shatter it. The last is readily removed because of the unchanneled plate at the toe tip and the outsole may then be attached in any desired manner, the fastenings shown or stitches 30 being placed 15 in the channel, after which the tempered flap may be cemented down, having a flat smooth insole except at the toe tip where the foot is not in contact with the insole.

I do not claim broadly a last having a 20 cavity constructed and arranged to hold

means for tempering a portion of a shoe on a last, nor do I claim the disclosed method of manufacturing shoes comprising maintaining an internal channel flap in temper while the shoe is on a last, since these mat- 25 ters are not my invention.

Having described my invention, what I claim as new and desire to secure by Letters Patent of the United States is:—

1. A shoe last having a waterproof bottom and having a cavity in said bottom constructed and arranged to hold a moistened pad. 30

2. A shoe last having a cavity in its bottom constructed and arranged to receive a 35 channel flap, the rim of the bottom around the cavity being composed of fiber.

In testimony whereof I have signed my name to this specification.

JOHN C. SCHELTER.
